US00D881184S

(12) **United States Design Patent** (10) Patent No.: **US D881,184 S**
(45) Date of Patent: **** Apr. 14, 2020**

(54) **COMMUNICATION TERMINAL**

(71) Applicant: **I.E.R.**, Suresnes (FR)

(72) Inventor: **Thibaut Frezal**, Draveil (FR)

(**) Term: **15 Years**

(21) Appl. No.: **35/504,035**

(22) Filed: **Sep. 14, 2017**

(80) **Hague Agreement Data**

Int. Filing Date: **Sep. 14, 2017**

Int. Reg. No.: **DM/098509**

Int. Reg. Date: **Sep. 14, 2017**

Int. Reg. Pub. Date: **Dec. 1, 2017**

(30) **Foreign Application Priority Data**

Mar. 14, 2017 (EM) 003799808-0004

(51) **LOC (12) Cl.** **14-02**

(52) **U.S. Cl.**

USPC **D14/307**

(58) **Field of Classification Search**

USPC D14/126, 302-307, 900-902; D20/10; D21/325, 332, 369, 370
